Specification for Design.

Patented Feb. 27, 1912.

Application filed October 28, 1910. Serial No. 589,617. Term of patent 7 years.

To all whom it may concern:

Be it known that I, SAMUEL S. SAMPLINER, a citizen of the United States, residing at Cleveland, in the county of Cuyahoga and State of Ohio, have invented a new, original, and ornamental Design for Flat-Knit Neck-scarfs or Mufflers, of which the following is a specification, reference being had to the accompanying drawing, forming a part thereof.

Figure 1 of said drawing is a plan-view of a neck-scarf or muffler, showing my new design, and Fig. 2 is a rear view of said muffler, showing the ornamental neck-portion and end-portions in their position, as worn.

The design is characterized by two ornamental end-portions in substantial alinement; two diagonally extending plainer por-

tions, and an ornamental intermediate portion off-set, but substantially parallel with said end portions. Plain and substantially parallel borders extend the entire length of the article, exhibiting straight edges for the three ornamental portions having a zig-zag appearance, and two substantially parallel stripes, conforming both to the zig-zag and plainer portions of the article, extend its entire length.

I claim:

The ornamental design for a flat-knit neck scarf, or muffler, as shown and described.

SAMUEL S. SAMPLINER.
